SAFETY CONTROL SYSTEM FOR GAS BURNERS

Richard Shottenfeld, Jamaica, N. Y., assignor to
Ensign Ribbon Burners, Inc., Pelham Manor,
N. Y., a corporation of New York

Application May 18, 1951, Serial No. 226,965

2 Claims. (Cl. 158—124)

1

This invention relates to gas burners equipped with electric spark ignition devices for currently insuring ignition of the gas by the spark. Such a spark is produced by current supplied by a so-called ignition transformer which delivers to a pair of electrodes an alternating current of high enough voltage to maintain a spark jumping the air gap between the electrodes.

More specifically, this relates to improvements in safety devices or safety control systems for automatically shutting off the gas supply to the burner in case of failure of the ignition spark.

Automatic safety devices or safety control systems are known for shutting off the gas in case of spark failure such as caused by failure of the power supply or by a variety of faults that may develop in the ignition system itself.

Such ignition systems usually employ an ignition transformer capable of producing an output voltage of the order of 5000 volts across the open circuited secondary which voltage is provided for insuring the spark to break down the air gap between the spark electrodes. Such ignition transformers are designed to deliver an output or secondary current that is never in excess of a desired limit value, for instance of the order of 15 milliamperes. In this way the transformer secondary current is never allowed to exceed a desired predetermined safe value irrespective of the load across the secondary. This means that the current is self-limiting and maintains itself substantially at the predetermined value.

Because of the high value of the voltage needed for operating the spark in such devices it is inadvisable to utilize voltage as a criterion of spark operation, from which to derive the desired gas valve control, and it is preferable to utilize as the operating criterion the secondary current flowing through the spark circuit. Thus a voltage-operated control system is to be distinguished from a current-operated system.

However, it is because of the aforementioned self-limiting characteristics of the transformer current that the current-operated devices lack the ability to distinguish between a current that is spark-producing and a current passing through the electrodes when there is no spark as in the case of short-circuiting of the electrodes.

Therefore, it is a problem in such known current-operated devices that, while effective in case

5 of systemic or other faults, they will fail to shut off the gas supply when the fault is due to short-circuiting of the electrodes for example by a metal particle accidentally bridging the air gap between the electrodes when current may continue to pass through the electrodes even though producing no spark.

It is an object of this invention to provide an improved safety control device or system which, even though current-operated, provides added safety by effecting gas shut off automatically in case of short-circuiting of the spark electrodes; and more particularly to provide such a control system that of itself is simple and relatively inexpensive to produce, as well as simple and inexpensive to maintain, and which is capable of being operated from a single relay power source in a manner which provides a high degree of safety with respect to other components of the system, in that it will cause the gas valve to close in the event of failure of such a component.

This object is attained by utilizing as a criterion of spark operation for gas valve control, certain differences in the characteristics or wave form of the secondary alternating current when the spark functions normally, and the characteristics or wave form of the secondary current when no spark is maintained as when the spark gap is shorted, that is by utilizing such difference of the wave forms to effect gas shut-off as and when the current changes from one wave form to the other. The wave form of the current in case of short circuit of the spark gap is that of the familiar continuous uninterrupted smooth wave form of an ordinary alternating current. By contrast, when the spark functions normally across the air gap, the current wave form is that of an interrupted wave which, characteristically, shows a rapid increase of the magnitude of the current shortly after the beginning of each half wave and a rapid decrease shortly before the end of each half wave. In this way there appears between each such rapid decrease and increase an interruption of the spark-producing current. In other words, there occurs an abnormally rapid decrease in the magnitude of the current before, and an abnormally rapid increase in the magnitude of the current after each interruption as distinct from the smooth uninterrupted transitions from one half wave to the next of the fa-

miliar smooth sinusoidal wave form of an alternating current. These rapid increases and decreases in the magnitude of the spark-producing current constitute high frequency components thereof.

These characteristics of the interrupted wave form are due to the fact that for a short period of time before and after the instant of zero-secondary-voltage that voltage is insufficient to break down the air gap between the electrodes. That is to say, during each half cycle the secondary voltage must first build up to a critical value in order that the spark may start, whereas the spark stops when the voltage falls below a critical value. Consequently, there is one starting and one stopping of the spark during each half cycle of the secondary voltage wave. In this way, as the spark establishes itself across the air gap, the secondary current rises almost instantaneously from zero to near the maximum limit value permitted by the transformer itself, and conversely as the spark stops the current falls almost instantaneously from near the maximum limit value to zero.

This invention provides gas valve controlling means which, while under the influence of the characteristics of the current of interrupted wave form, keep the gas valve open concurrently with the normal functioning of the spark, but which controlling means close the gas valve in response to a change of current from the interrupted to the non-interrupted wave form, which change is the criterion of spark failure utilized according to this invention for automatically effecting the gas shut-off.

This invention provides a control system which responds to the characteristic rapid increases and decreases in the magnitude of the current by maintaining the gas valve open while the ignition spark operates normally, and by closing the valve in the absence of such rapid increases and decreases as due to a short circuit across the gap when no spark occurs even though a current of uninterrupted wave form is passing through the electrodes. In other words, this control system keeps the gas valve open only as long as it is under the influence of the rapid increases and decreases of the secondary spark producing current, but causes the valve to close as soon as the current assumes a wave form in which these rapid current changes are lacking.

Further particularized, this invention provides gas valve actuating means responsive to the rapid changes in the magnitude of the current and non-responsive to the relatively gradual sinusoidal cyclic changes which characterize the wave form when no sparking takes place. Such selective responsiveness is attained by providing control means capable of deriving or abstracting energy only from a current of sufficiently rapid change in magnitude such as the spark producing interrupted current wave form, and supplying that energy through relay means to control the gas valve to hold it open, and to close the valve in the absence of such energy. That is to say, the invention provides frequency-discriminating circuit means associated with the spark producing circuit for selectively abstracting energy from the high-frequency components of the spark producing current and adapted to supply such energy for control purposes during the functioning of the spark.

According to one feature, a device within the control system for abstracting energy for valve

control purposes comprises a resonant circuit coupled with and under the influence of the spark producing current.

A resonant circuit of itself is well known, and it comprises an inductance and a capacitance so connected that when a current passing through the resonant circuit is changed abruptly in magnitude, then the voltage across this circuit due to such abrupt change does not itself change abruptly but rather changes as an oscillatory function of time namely as an exponentially damped sinusoidal wave.

Such abrupt change of current may be said to shock the resonant circuit into oscillations at its resonant frequency comparable to a bell being struck into ringing or a resilient mechanical system being subjected to a sudden impact causing it to vibrate when the energy of the impact is absorbed in and dissipated by the vibrations. Similarly, the electrical shock imparted to the resonant circuit by the rapid increase or decrease of the current is absorbed in and dissipated by the subsequent oscillations of a resonant current and voltage resulting from the shock within that circuit. Hence the resonant circuit is said to "ring" (like a bell) at its resonant frequency.

This frequency of resonance, according to this feature, is very much higher than the frequency of the power supply to the ignition transformer. For example, while the frequency of the power supply to the ignition transformer may be 60 cycles per second, the frequency of the resonant circuit may be on the order of several million cycles per second. Furthermore, this feature provides that the highest peak voltage appearing across the resonant circuit will be of the order of 100 to 200 volts, whereas the spark producing peak voltage may be of the order of 7500 volts. Therefore the variations or oscillations in the voltage of the resonant circuit will have no appreciable effect on the spark, even though they are utilized according to this invention to provide energy for automatically controlling the operation of the gas valve. On the other hand, when no spark is being produced because of short circuiting of the electrodes, then the current that passes through the resonant circuit, because of its uninterrupted wave form, produces only a voltage that is practically zero or negligibly small.

At any rate, during each "ring" of the resonant circuit the voltage across that circuit varies as a function of time and follows the law of an exponentially damped sinusoidal wave which is an expression of the fact that the energy imparted to the resonant circuit by abrupt current change is being absorbed by and dissipated in the circuit losses. The damped sinusoidal wave represents what is herein termed a high frequency component of the spark producing transformer secondary current which in turn possesses a relatively low frequency at relatively high voltage.

According to this invention, a portion of the energy in the ringing resonant circuit is utilized through relay means for controlling the gas valve and to hold it open only during the normal functioning of the spark.

According to a feature, since the energy furnished by a single "ring" of the resonant circuit may be insufficient to operate directly a practical type of relay, provision is made for the relay to be actuated by the accumulated energy of a sequence of such "rings."

According to another feature, the energy needed for actuating the gas valve-controlling relay means is converted from A.-C. form to D.-C. form and as such is accumulated in a condenser. In other words, the aforementioned portion of the energy in the resonant circuit, to be utilized for controlling the gas valve, is transferred to and stored within the condenser. That is, the condenser, receiving increments of energy with each "ring" of the resonant circuit, is enabled to hold a charge thus accumulated by a one-way conductor such as a rectifier functionally interposed between the condenser and the source of energy as represented by the resonant circuit when in a state of "ringing." Thus the condenser becomes gradually charged to a D.-C. voltage substantially equal to the highest peak voltage attained by the damped sinusoidal voltage wave of the "ringing." This D.-C. voltage is utilized through the relay action of a current amplifier electronic tube to hold the gas valve open while the spark functions normally. That is, the D.-C. voltage is impressed upon the input electrode or grid of the tube which in turn acts in proportion to such impressed voltage to vary the flow of current through the tube from an independent auxiliary power source employed for actuating the gas valve proper. That is, the D.-C. voltage from the condenser operates through the tube to hold the gas valve open only as long as the condenser remains sufficiently charged, provision being made for the condenser to discharge automatically and for the D.-C. voltage to drop to zero within a predetermined period of time, after the supply of energy increments from the "ringing" of the resonant circuit ceases, due to spark failure. The amplifier tube circuit is designed to shut off the auxiliary power supply when the D.-C. grid voltage drops sufficiently or becomes zero to effect automatically the closing of the gas valve. In this way cumulative energy of a sequence of damped sinusoidal waves is utilized to control the desired functioning of the gas valve.

Summarizing, the control system comprises four functional operating units, namely, (a) a gas burner unit comprising a gas burner, a pair of ignition spark electrodes for the burner, a gas control valve for the burner, and an electrically energized gas valve actuating device to hold the valve open when energized and to close it when deenergized; (b) an ignition unit comprising an ignition transformer for supplying spark current to the electrodes, and a spark-detecting resonant circuit functionally coupled with the transformer in such a manner as to abstract energy from the spark producing current; (c) a rectifying energy-storing unit comprising a rectifier for changing the abstracted A.-C. energy to D.-C. energy, a condenser for receiving rectified energy from the spark-detecting resonant circuit, and a resistor in parallel with the condenser and dimensioned to discharge the condenser within a predetermined time after the supply of energy has ceased due to spark failure; (d) a relay unit comprising an electronic amplifier tube having at least an anode, a grid, and a cathode, and controlled by the D.-C. voltage of the charge stored in the condenser so as to energize the valve actuating means or solenoid coil only while the spark is functioning normally.

In terms of circuits the control system ac-

cording to this invention presents itself as follows:

The ignition transformer secondary current contains high frequency components only when the ignition spark is functioning but not when the spark is absent due to the electrodes having become short circuited.

In conjunction with the ignition circuit there are provided frequency discriminating circuit means or a resonant circuit which is frequency discriminating in that it selectively abstracts energy from the high frequency component of the spark producing current, but remains non-responsive to any current in which the high frequency components are absent such as current passing through short circuited electrodes. The abstracted energy is supplied to a rectifying energy storing circuit where it is accumulated up to a predetermined voltage, from which circuit the accumulated energy is automatically discharged whenever the supply of energy ceases. This predetermined voltage being a manifestation of the stored energy is utilized in and by a relay power circuit comprising an amplifier tube the operation of which is governed by that voltage. That is, the voltage is impressed upon the grid of that amplifier tube in such a manner that the tube acts to pass current sufficient to actuate the valve operating means to hold the valve open as long as the energy supply and thereby the grid voltage are being maintained incident to the functioning of the spark, whereas the tube reduces or throttles the relay current sufficiently to close the gas valve when said energy supply ceases and the grid voltage drops to zero incident to cessation of the functioning of the spark.

The rectifying energy-storing circuit is connected across the frequency discriminating circuit means so as to receive the abstracted high-frequency energy for rectification, the resistor being in parallel with the filtering capacitance and adapted to automatically discharge stored energy to a lower control voltage upon cessation of the supply of abstracted energy.

A reference potential or ground of the control system is common to one of said spark electrodes, a first terminal of the frequency-discriminating resonant circuit, a first terminal of the filtering capacitance, and a first terminal of the relay power source, with the rectifier as of a polarity to render the second terminal of the filtering capacitance positive with respect to said reference potential in response to the presence of the spark. Furthermore, the solenoid coil has its first terminal connected with the power source at the reference potential, and its second terminal connected with the cathode of the amplifier tube, while the anode of the amplifier tube is connected with the second terminal of the power source, and the grid of the amplifier tube is connected to the second terminal of the filtering capacitance.

With these connections and polarities, and the spark absent, the amplifier tube current itself in passing through the solenoid coil produces a voltage drop biasing the cathode positive with respect to the reference potential thereby rendering that current self-limiting to a value insufficient to allow the gas valve to open; whereas, with the spark present, the voltage drop appearing across the filtering capacitance increases the current through the amplifier tube and the solenoid coil sufficiently to effect opening of the gas

A special safety factor characterizes this arrangement of the amplifier relay circuit, insofar as it offers the insurance of closing the gas valve in the event of failure of any of the components of the amplifier relay circuit. This is because of the fact that the bias on the grid of the amplifier tube required for closing the gas valve is derived from the passage of the tube current itself through the solenoid, so that any failure within this amplifier relay circuit, which would remove the aforementioned positive bias on the cathode of the amplifier tube, would at the same time de-energize the solenoid coil and thus allow the valve to close.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

In the drawings:

Figure 1 shows the gas burner having a spark electrode ignition system and a solenoid-operated gas supply valve, with the addition of the control system capable of discriminating between the interrupted spark producing wave form and the uninterrupted no-spark wave form of the ignition current for controlling the opening and closing of the gas valve.

Figures 2 to 7 are voltage and current diagrams illustrating characteristics of spark producing current and of the no-spark current, respectively; that is Figure 2 shows a voltage wave indicating the open-circuited voltage of the transformer secondary; Figure 3 indicates the uninterrupted current wave form of the no-spark current; Figure 4 indicates the interrupted wave form of the spark producing current; Figure 5 is an enlarged diagram indicating the resultant voltage of a half-wave of the spark producing current including the high frequency components; Figure 6 shows further enlarged the voltage of the high frequency components per se; Figure 7 is a half-wave diagram taken from Figure 4 and showing the spark producing current in coordination and time relationship to the Figures 5 and 6 diagrams.

Figure 8 shows the characteristic part of the ignition circuit to illustrate the computation of the resultant voltage of the Figure 5 diagram.

A gas burner 10 in Figure 1 may be of any conventional type receiving its gas supply from a gas supply pipe 11 through a usual nozzle 12 surrounded by an annular passage 13 for admitting combustion air to mix with gas from the nozzle, air and gas to mix in the short length of mixing pipe 14 before entering the burner head proper here shown to be in the form of a ribbon burner 15.

The gas supply pipe 11 has a solenoid-actuated control valve 16 as well as a hand-operated shut-off valve 17. The valve 16 has an actuating lever 16^a connected to a tension spring 18 for holding the valve closed by urging the lever 16^a in the direction of arrow A1. The lever is also connected to an armature 19 for opening the valve 16 by moving the actuating lever in the direction of arrow A2 against the tension of spring 18 when the armature is drawn in that direction by energization of a valve-opening solenoid 20.

The solenoid 20 is here shown to be energizable as from a power source P, for instance 110 volts 60 cycles, through the operation of a solenoid-actuated relay switch 20^a which comprises a pair of relay contacts 20^b and 20^c, an armature 20^d and a solenoid coil 20^e energizable from the power source P for moving the armature to close the contacts against the tension of spring 20^f.

The burner 10 together with appurtenances 10 such as the valve 17, the valve 16 with solenoid-actuated lever 16^a, and solenoid-actuated relay switch 20^a, constitute what is herein termed the burner unit A.

The burner head 15 is provided with a pair of spark electrodes indicated at 21 and 22, electrode 21 having a ground 23 to make it the low tension electrode, with electrode 22 representing the high tension electrode. These electrodes are supplied with current from an ignition transformer 24 having a primary coil 25 and a secondary coil 26 which coils are briefly termed the primary and the secondary respectively. The primary 25 having terminals 27 and 28 is shown to be supplied with the usual 110 volt 60 cycle current through power line conductors 29 and 30 from line terminals 31 and 32; the secondary 26 has terminals 33 and 34. Terminal 33 of the secondary is connected to the high tension spark electrode 22 through a conductor 35, while terminal 34 of the secondary is connected to the low tension spark electrode 21 through conductors 36 and 37 by way of interposed frequency discriminating circuit means in the form of a resonant circuit 38 which comprises an inductance 39 and a capacitance 40 connected in parallel. That is, the conductor 36 at point 41 divides into a pair of branches 42 and 43, while the conductor 37 at point 44 splits into a pair of branches 45 and 46.

The circuit across the transformer secondary coil 26, called the secondary circuit, comprises the secondary coil 26, the conductor 35, the spark electrodes 21 and 22 with air gap G between them, and the conductors 37 and 36, as well as the interposed resonant circuit 38. This secondary transformer circuit may carry either a spark producing current or a no-spark current depending upon whether the circuit is functioning normally or whether the electrodes have become short-circuited.

The secondary voltage of the ignition transformer 24 is usually of the order of 5000 volts across the open circuit, and the transformer itself is of the current-limiting type, that is the type delivering a secondary current not in excess of a predetermined magnitude, for instance, of the order of 15 milliamperes, irrespective of the magnitude of the load across the circuit, that is irrespective of whether the spark across the electrodes is functioning normally or whether the electrodes have become short-circuited.

The transformer 24 together with the resonant circuit 38 constitutes what is herein termed the ignition unit B. The primary and the secondary transformer circuits including the spark electrodes 21 and 22 are herein termed the ignition system.

The invention is based upon the concept of utilizing, for control purposes, the difference between the characteristic of the spark producing current and that of the no-spark current.

According to this invention, the resonant circuit 38 serves for abstracting high frequency energy from the spark producing circuit, that energy to be utilized in producing the desired control effects. Such energy manifests itself in the form

According to another feature, the energy needed for actuating the gas valve-controlling relay means is converted from A.-C. form to D.-C. form and as such is accumulated in a condenser. In other words, the aforementioned portion of the energy in the resonant circuit, to be utilized for controlling the gas valve, is transferred to and stored within the condenser. That is, the condenser, receiving increments of energy with each "ring" of the resonant circuit, is enabled to hold a charge thus accumulated by a one-way conductor such as a rectifier functionally interposed between the condenser and the source of energy as represented by the resonant circuit when in a state of "ringing." Thus the condenser becomes gradually charged to a D.-C. voltage substantially equal to the highest peak voltage attained by the damped sinusoidal voltage wave of the "ringing." This D.-C. voltage is utilized through the relay action of a current amplifier electronic tube to hold the gas valve open while the spark functions normally. That is, the D.-C. voltage is impressed upon the input electrode or grid of the tube which in turn acts in proportion to such impressed voltage to vary the flow of current through the tube from an independent auxiliary power source employed for actuating the gas valve proper. That is, the D.-C. voltage from the condenser operates through the tube to hold the gas valve open only as long as the condenser remains sufficiently charged, provision being made for the condenser to discharge automatically and for the D.-C. voltage to drop to zero within a predetermined period of time, after the supply of energy increments from the "ringing" of the resonant circuit ceases, due to spark failure. The amplifier tube circuit is designed to shut off the auxiliary power supply when the D.-C. grid voltage drops sufficiently or becomes zero to effect automatically the closing of the gas valve. In this way cumulative energy of a sequence of damped sinusoidal waves is utilized to control the desired functioning of the gas valve.

Summarizing, the control system comprises four functional operating units, namely, (a) a gas burner unit comprising a gas burner, a pair of ignition spark electrodes for the burner, a gas control valve for the burner, and an electrically energized gas valve actuating device to hold the valve open when energized and to close it when deenergized; (b) an ignition unit comprising an ignition transformer for supplying spark current to the electrodes, and a spark-detecting resonant circuit functionally coupled with the transformer in such a manner as to abstract energy from the spark producing current; (c) a rectifying energy-storing unit comprising a rectifier for changing the abstracted A.-C. energy to D.-C. energy, a condenser for receiving rectified energy from the spark-detecting resonant circuit, and a resistor in parallel with the condenser and dimensioned to discharge the condenser within a predetermined time after the supply of energy has ceased due to spark failure; (d) a relay unit comprising an electronic amplifier tube having at least an anode, a grid, and a cathode, and controlled by the D.-C. voltage of the charge stored in the condenser so as to energize the valve actuating means or solenoid coil only while the spark is functioning normally.

In terms of circuits the control system ac-

cording to this invention presents itself as follows:

The ignition transformer secondary current contains high frequency components only when the ignition spark is functioning but not when the spark is absent due to the electrodes having become short circuited.

In conjunction with the ignition circuit there are provided frequency discriminating circuit means or a resonant circuit which is frequency discriminating in that it selectively abstracts energy from the high frequency component of the spark producing current, but remains non-responsive to any current in which the high frequency components are absent such as current passing through short circuited electrodes. The abstracted energy is supplied to a rectifying energy storing circuit where it is accumulated up to a predetermined voltage, from which circuit the accumulated energy is automatically discharged whenever the supply of energy ceases. This predetermined voltage being a manifestation of the stored energy is utilized in and by a relay power circuit comprising an amplifier tube the operation of which is governed by that voltage. That is, the voltage is impressed upon the grid of that amplifier tube in such a manner that the tube acts to pass current sufficient to actuate the valve operating means to hold the valve open as long as the energy supply and thereby the grid voltage are being maintained incident to the functioning of the spark; whereas the tube reduces or throttles the relay current sufficiently to close the gas valve when said energy supply ceases and the grid voltage drops to zero incident to cessation of the functioning of the spark.

The rectifying energy-storing circuit is connected across the frequency discriminating circuit means so as to receive the abstracted high-frequency energy for rectification, the resistor being in parallel with the filtering capacitance and adapted to automatically discharge stored energy to a lower control voltage upon cessation of the supply of abstracted energy.

A reference potential or ground of the control system is common to one of said spark electrodes, a first terminal of the frequency-discriminating resonant circuit, a first terminal of the filtering capacitance, and a first terminal of the relay power source, with the rectifier as of a polarity to render the second terminal of the filtering capacitance positive with respect to said reference potential in response to the presence of the spark. Furthermore, the solenoid coil has its first terminal connected with the power source at the reference potential, and its second terminal connected with the cathode of the amplifier tube, while the anode of the amplifier tube is connected with the second terminal of the power source, and the grid of the amplifier tube is connected to the second terminal of the filtering capacitance.

With these connections and polarities, and the spark absent, the amplifier tube current itself in passing through the solenoid coil produces a voltage drop biasing the cathode positive with respect to the reference potential thereby rendering that current self-limiting to a value insufficient to allow the gas valve to open; whereas, with the spark present, the voltage drop appearing across the filtering capacitance increases the current through the amplifier tube and the solenoid coil sufficiently to effect opening of the gas valve.

A special safety factor characterizes this arrangement of the amplifier relay circuit, insofar as it offers the insurance of closing the gas valve in the event of failure of any of the components of the amplifier relay circuit. This is because of the fact that the bias on the grid of the amplifier tube required for closing the gas valve is derived from the passage of the tube current itself through the solenoid, so that any failure within this amplifier relay circuit, which would remove the aforementioned positive bias on the cathode of the amplifier tube, would at the same time de-energize the solenoid coil and thus allow the valve to close.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

Figure 8 shows the characteristic part of the ignition circuit to illustrate the computation of the resultant voltage of the Figure 5 diagram.

A gas burner 10 in Figure 1 may be of any conventional type receiving its gas supply from a gas supply pipe 11 through a usual nozzle 12 surrounded by an annular passage 13 for admitting combustion air to mix with gas from the nozzle, air and gas to mix in the short length of mixing pipe 14 before entering the burner head proper here shown to be in the form of a ribbon burner 15.

The gas supply pipe 11 has a solenoid-actuated control valve 16 as well as a hand-operated shut-off valve 17. The valve 16 has an actuating lever 16^a connected to a tension spring 18 for holding the valve closed by urging the lever 16^a in the direction of arrow A1. The lever is also connected to an armature 19 for opening the valve 16 by moving the actuating lever in the direction of arrow A2 against the tension of spring 18 when the armature is drawn in that direction by energization of a valve-opening solenoid 20.

The solenoid 20 is here shown to be energizable as from a power source P, for instance 110 volts 60 cycles, through the operation of a solenoid-actuated relay switch 20^a which comprises a pair of relay contacts 20^b and 20^c, an armature 20^d and a solenoid coil 20^e energizable from the power source P for moving the armature to close the contacts against the tension of spring 18.

The burner 10 together with appurtenances such as the valve 17, the valve 16 with solenoid-actuated lever 16^a, and solenoid-actuated relay switch 20^a, constitute what is herein termed the burner unit A.

The burner head 15 is provided with a pair of spark electrodes indicated at 21 and 22, electrode 21 having a ground 23 to make it the low tension electrode, with electrode 22 representing the high tension electrode. These electrodes are supplied with current from an ignition transformer 24 having a primary coil 25 and a secondary coil 26 which coils are briefly termed the primary and the secondary respectively. The primary 25 having terminals 27 and 28 is shown to be supplied with the usual 110 volt 60 cycle current through power line conductors 29 and 30 from line terminals 31 and 32; the secondary 26 has terminals 33 and 34. Terminal 33 of the secondary is connected to the high tension spark electrode 22 through a conductor 35, while terminal 34 of the secondary is connected to the low tension spark electrode 21 through conductors 36 and 37 by way of interposed frequency discriminating circuit means in the form of a resonant circuit 38 which comprises an inductance 39 and a capacitance 40 connected in parallel. That is, the conductor 36 at point 41 divides into a pair of branches 42 and 43, while the conductor 37 at point 44 splits into a pair of branches 45 and 46.

The circuit across the transformer secondary coil 26, called the secondary circuit, comprises the secondary coil 26, the conductor 35, the spark electrodes 21 and 22 with air gap G between them, and the conductors 37 and 38, as well as the interposed resonant circuit 38. This secondary transformer circuit may carry either a spark producing current or a no-spark current depending upon whether the circuit is functioning normally or whether the electrodes have become short-circuited.

The secondary voltage of the ignition transformer 24 is usually of the order of 5000 volts across the open circuit, and the transformer itself is of the current-limiting type, that is the type delivering a secondary current not in excess of a predetermined magnitude, for instance, of the order of 15 milliamperes, irrespective of the magnitude of the load across the circuit, that is irrespective of whether the spark across the electrodes is functioning normally or whether the electrodes have become short-circuited.

The transformer 24 together with the resonant circuit 38 constitutes what is herein termed the ignition unit B. The primary and the secondary transformer circuits including the spark electrodes 21 and 22 are herein termed the ignition system.

The invention is based upon the concept of utilizing, for control purposes, the difference between the characteristic of the spark producing current and that of the no-spark current.

According to this invention, the resonant circuit 38 serves for abstracting high frequency energy from the spark producing circuit, that energy to be utilized in producing the desired control effects. Such energy manifests itself in the form

of a damped sinusoidal voltage wave across the terminals 41 and 44 of the resonance circuit. The characteristics and functions of a resonant circuit as such are known. Suffice it to say at this point that the high frequency energy components of the spark producing current, as represented by the damped sinusoidal waves manifest themselves in the "ringing" of the resonant circuit as and when the rapid increases and the rapid decreases occur in the interrupted wave form of the spark producing current. Instead of allowing that energy to dissipate itself entirely within the resonant circuit 38, this invention provides an energy-converting- and energy-storing circuit across the terminals of the resonant circuit, namely across the terminal 34 and ground 23 which is the same as ground 59. This energy-converting, and storing circuit serves to convert a portion of the high frequency energy to D.-C. energy and for continuously storing such converted energy. The stored energy is utilized for holding the gas valve 16 open only as long as such energy is supplied from the resonant circuit, the valve to close when such energy ceases to be supplied due to failure of the spark as when the electrodes 21 and 22 have become short-circuited.

The manner in which the energy supplied by the resonant circuit 38 is utilized to effect the desired control will be explained in greater detail below in conjunction with a discussion of the Figures 2 to 7 diagrams illustrating the difference in the characteristics of the spark producing current and of the no-spark current respectively.

The energy converting and storing circuit comprises a rectifier here shown in the form of a half-wave rectifying electronic tube 48 termed half-wave rectifier having an anode 48^a with terminal T₃ and a cathode 48^b with terminal T₄, and a condenser 49 with a resistor R connected in parallel therewith, the resistor having terminals T₁ and T₂. The resistor R functions as a by-pass for the condenser 49 to automatically discharge the condenser within a predetermined time after the supply of energy ceases, such function and its significance to be explained further below.

A conductor 50 leads from terminal 34 of the transformer secondary to the rectifier anode 48^a. The cathode 48^b of the rectifier has a terminal T₄ from which a conductor 52 leads to a branch point 53 for a pair of conductors 54 and 55, branch 54 leading to terminal T₁ of resistor R and branch 55 leading to the positive plate 49^a of condenser 49. The parallel connection of resistor R with condenser 49 is completed by a pair of conductors 56 and 57 leading respectively from resistor terminal T₂ and from the negative plate 49^b of condenser 49 to a juncture point 58 connected to a ground 59. In this way the energy converting and storing circuit is connected across or in parallel with the resonant circuit 38. The rectifier tube 48 constitutes together with the condenser 49 and with the resistor R an energy storing unit C indicated as such by the dot-and-dash line frame around it.

The condenser 49 and the resistor R are so dimensioned with respect to each other that the resistor permits just enough leakage of energy therethrough to allow the condenser to be charged to the peak voltage of the damped sinusoidal energy waves, yet so that the condenser will discharge by way of the resistor within a predetermined length of time after the supply of high frequency energy to the condenser has ceased in case the spark electrodes 21 and 22 have become short-circuited.

As long as high frequency energy is supplied from the ignition system to the energy storing circuit, that circuit manifests its charge by a D.-C. voltage at the output or cathode terminal T₄ of rectifier 48, which voltage drops to zero when the supply of high frequency energy ceases. This D.-C. voltage is a criterion of the functioning of the spark electrodes 21 and 22, and is utilized to furnish control impulses for closing the gas valve 16 whenever this voltage disappears and to keep the valve open as long as the voltage is maintained.

A relay circuit is provided for actuating the gas valve 16 with an electronic tube 60 controlling the current in that circuit. The electronic tube 60 has an anode 61 with terminal 61^a, a cathode 62 with terminal 62^a, and a control grid 63, which tube is herein also identified as a relay unit D indicated as such by a dot-and-dash line frame around it. A conductor 64 leads from terminal T₄ of rectifier cathode 48^b to control grid 63 for impressing upon the grid the D.-C. voltage of storage condenser 49.

The amplifier tube 60 is designed to pass therethrough a relay current of sufficient magnitude to energize solenoid devices for holding the gas valve 16 open as long as the grid voltage is maintained incident to the normal functioning of the ignition spark and to throttle such current sufficiently to de-energize the solenoid devices to allow the gas valve to close when the grid voltage drops to zero incident to a cessation of the ignition spark.

A relay power circuit to furnish current for actuating the gas valve comprises a conductor 65 leading from terminal 28 on power line 30 to anode terminal 61^a of tube 60, the tube 60, a conductor 66 leading from cathode terminal 62^a of tube 60 to a terminal 67 of solenoid coil 20^e, the solenoid coil 20^e, a conductor 68 leading from the other terminal 69 of solenoid coil 20^e to a point 70, a conductor 71 leading from point 70 to a point 72 connected to ground 59, and a conductor 73 leading from point 72 to a terminal 74 on power line 29.

The solenoid 20^e when energized draws the armature 20^d thus closing contacts 20^b and 20^c of relay switch 20^a against the tension of a spring 20^f, thus closing a secondary relay circuit which comprises a conductor 76 leading from anode terminal 61^a connecting with power line 30 to terminal T₆ of stationary switch contact 20^b, relay switch contacts 20^b and 20^c, a conductor 77 leading from terminal T₆ of movable switch contact 20^c to terminal 20^g of solenoid coil 20, solenoid coil 20 and a conductor 78 leading from terminal 20^h to point 70 connecting with the power line 29.

Now follows the description and the discussion of the Figures 2 to 7 diagrams, so that the manner in which the abstracted high frequency energy is utilized may be more fully understood.

The wave shown in the Figure 2 diagram indicates the open-circuited voltage V of the transformer secondary and as a function of time, and by establishing the points of zero voltage M, N, O furnishes the time cycle as a basis of comparison of the uninterrupted wave form of the no-spark current of Figure 3 with the interrupted wave form of the spark producing current in Figure 4. Corresponding points of zero voltage are indicated at M₁, N₁, O₁ in Figure 3, and at M₂, N₂, O₂ in Figure 4. The voltage wave of Figure 2 is composed of a series of half-waves indicated by the lengths H on the abscissa, that 75 is the distance H between any two zero points.

For the purpose of comparison the lengths H are also indicated in Figures 3 and 4.

The Figure 3 diagram illustrates the uninterrupted smooth wave form of the no-spark current I composed of half-waves H the actual voltage of which need not be that of Figure 2, the half-waves being defined by the points of zero voltage M_1 , N_1 , O_1 .

In the interrupted wave form of the spark producing current in Figure 4 a half-wave of the length H comprises characteristically a spark producing current I_1 . The current I_1 extends over a length H_1 on the abscissa beginning a distance S_1 from the point M_2 of zero voltage and ending a distance S_2 from the point N_2 of zero voltage. This current I_1 comprises (see also in Figure 7) an initial steeply rising portion p_1 defined by points "a" and "b"; a major intermediate portion p_2 of shallow convexity and defined by points "b" and "c" with a maximum value I_{max} , and a steeply falling portion p_3 defined by points "c" and "d". Measured upon the abscissa the portions p_1 , p_2 , p_3 of current I_1 are defined by the horizontal distances d_1 , d_2 , d_3 . That is to say, the spark and therewith the current starts only after the open circuit voltage has reached a value V_1 (see Figure 5) sufficient to break down the spark gap G . Starting at point "a" the current rises rapidly to point "b" through a time interval defined by the distance d_1 to a value I_1 which is nearly that of the maximum value I_{max} because of the current limiting characteristic of the transformer 24. The current is maintained along the shallow convex portion along the line P_2 from point "b" to point "c" through a time interval d_2 producing and maintaining a spark.

At point "c" when the voltage reaches a value V_e (see Figure 5) insufficient to maintain the spark, the spark disappears at that voltage as the current drops rapidly from a value I_e to zero from point "c" to point "d" along the line P_3 through a time interval d_3 . The concurrent spark load voltage V_s is indicated in Figure 5 between points "e" and "f" corresponding to points "b" and "c" in Figure 7, by a line of shallow convexity with a maximum voltage V_{max} .

The initial rapidly rising portion P_1 of the current provides within the transformer secondary circuit a high frequency energy component manifesting itself in the form of a damped sinusoidal voltage wave W_1 shown per se in Figure 6 to extend through a time interval d_4 . This high frequency wave has a starting point "g" which corresponds to point "e" in Figure 5 and to point "b" in Figure 7. Similarly, the rapidly falling terminal portion P_3 of the current provides within the transformer secondary circuit a high frequency energy component manifesting itself in the form of a damped sinusoidal voltage wave W_t (see Figure 6) extending through a time interval d_5 . This high frequency wave has a starting point "h" which corresponds to point "f" in Figure 5 and to point "d" in Figure 7. The absolute maximum initial voltages of the high frequency waves W_1 and W_t are indicated at F_{max} and F'_{max} respectively.

The high frequency waves W_1 and W_t of Figure 6 appear as waves W_1' and W_t' embodied in the Figure 5 diagram of the spark producing voltage half-wave V_s , so that the voltage indicated by the full line in Figure 5 is the resultant voltage appearing across the spark electrodes 21 and 22. The resultant spark producing voltage due to the appearance of the high frequency

waves is computable as $V_s = e - e_1$ (see Figure 8 auxiliary wiring diagram), hence the peaks of waves W_1 and W_t point in opposite directions to that of waves W_1' and W_t' .

Operation

When the ignition system as such is functioning normally, that is when a spark appears across the electrodes 21 and 22, such spark is being maintained by the interrupted current wave of Figures 4 and 7 together with the spark producing voltage V_s of Figure 5 including the high frequency components W_1' and W_t' . Such spark producing current is delivered by the secondary 26 of transformer 24 through the intermediary of the resonant circuit 38, the transformer primary 25 being supplied with the usual 110 volt 60 cycle alternating current indicated by power source P and line terminals 31 and 32.

A portion of the high frequency energy represented by the voltage waves W_1 and W_t appearing across points 34 and 44 of the resonant circuit is absorbed and stored by the energy converting and storing unit C connected across resonant circuit 38 at points 34 and 44 by way of grounds 23 and 59. That is to say, whenever the instantaneous value of the high frequency voltage waves W_1 and W_t as measured at the anode 48^a of rectifier 48 becomes more positive than the cathode 48^b of rectifier 48, then current flows through the rectifier 48 into the condenser 49 raising the difference of potential or voltage between condenser plates 49^a and 49^b. However, when the anode 48^a becomes more negative than the cathode 48^b any flow of current through the rectifier is blocked. Thus a portion of the high frequency energy is rectified.

A portion of the condenser charge leaks out continuously by way of the discharge resistor R in parallel with the condenser 49. However, the energy thus leaking out from the condenser through the discharge resistor R is small as compared with the rectified energy supplied thereto, so that the condenser attains and holds a charge of sufficient voltage to be utilized in maintaining and sustaining a control effect whereby the gas valve 16 is kept open. This control effect is attained by the condenser voltage appearing at point T₄ being impressed upon the control grid 63 of electronic tube 60. The tube operates so that it passes relay current in proportion to the magnitude of the impressed voltage, that is, the more positive the grid becomes, the larger is the current passed by the tube. The grid voltage thus impressed is sufficient to pass relay current from line terminal 28 to terminal 74 to energize solenoid coil 20^a drawing armature 20^d to close contacts 20^b and 20^c against the tension of spring 20^f. The closing of these contacts in turn closes a circuit from supply terminal 28 to terminal 74 to energize the solenoid coil 20 for drawing in the armature 19 against the tension of spring 18 to hold open the gas valve 16. Consequently, as long as the spark functions normally across spark electrodes 21 and 22 the gas valve 16 is maintained open.

If the spark is absent, then there is also absent the phenomenon of the high frequency voltage waves W_1' and W_t' , so that rectified energy is no longer supplied to the condenser 49. In such case the condenser discharges through discharge resistor R. Concurrently the condenser voltage and thus the voltage on control grid 63 drops sufficiently to choke off the relay current which has so far been passing through the tube 60.

This causes solenoid coil 20^e to be deenergized allowing spring 20^f to open the contacts 20^b and 20^c. This in turn interrupts the energizing current for solenoid coil 20 allowing the spring 18 to close the gas valve 16, thus shutting off the supply of fuel to burner 10.

That is to say, the spark electrode 21, the terminal 44 of the frequency discriminating circuit means or resonant circuit 38, the terminal 69 of solenoid coil 20^e, the junction point 58 between the capacitance 49 and resistor R, and the line terminal 31 of power source P, all are connected together at what is herein termed the reference potential.

Furthermore, the polarity of the rectifier 48 is such that the junction point 53 between the capacitance 49 and resistor R is rendered positive with respect to the reference potential in response to the presence of the spark.

Thus, in the absence of the spark, the voltage across the filtering capacitance 49 drops to substantially zero placing grid 63 of amplifier tube 60 substantially at the reference potential. Concurrently a current will pass from terminal 28 of power source P through the amplifier tube 60 and through the solenoid coil 20^e to terminal 70 which is at the reference potential. This current sets up a voltage drop across the solenoid coil 20^e, which places the cathode 62 of amplifier tube 60 at a positive potential with respect to the reference potential.

This means that, with the grid 63 at reference potential and the cathode positive with respect to the reference potential, the grid then is actually negative with respect to the cathode, hence as the cathode becomes more positive with respect to the reference potential the current diminishes accordingly. That is to say, the characteristics of the amplifier tube and of the solenoid are so coordinated that in the absence of an adequate control voltage at terminal T₄ (in the absence of the spark), the current through amplifier tube 60 and solenoid 20^e is self-limiting and thus maintains itself at a value insufficient to effect the opening of the gas valve. This amplifier relay circuit (between power terminals 28 and 70) embodies a safety factor insofar as it insures the closing of the gas valve in the event of failure of any of the components of the amplifier relay circuit. This is due to the fact that the bias on the grid 63 required for closing the gas valve is derived from the passage of the tube current itself through the solenoid 20^e, so that any failure within this amplifier relay circuit, which would remove the aforementioned positive bias on the cathode 62, would at the same time de-energize the solenoid coil 20^e and thus allow the gas valve to close.

On the other hand, in the presence of the spark, with a sufficiently large voltage drop appearing across the filtering capacitance 49 when the grid 63 of amplifier tube 60 becomes biased to a higher positive potential with respect to the reference potential, such condition will increase the current passing through amplifier tube 60 and solenoid coil 20^e sufficiently to effect opening of the gas valve. In other words, as the grid 63 becomes more positive, the current through the tube 60 and through solenoid coil 20^e increases accordingly. The result is that when the grid 63 has attained a sufficiently high positive potential with respect to the reference potential, then the tube current will have increased to a value sufficient to effect opening of the gas valve.

Since this invention is based broadly upon the

concept of utilizing the high frequency components of the spark producing current for control purposes, it lies within the scope of the invention that the high frequency energy abstracting means can be embodied in means other than the specific parallel resonant circuit 38 shown. For example, instead of placing that resonant circuit in the low tension side of the transformer secondary circuit as shown in the Figure 1 embodiment, this resonant circuit may for example also be placed in the high tension side of the secondary, or in the low tension side of the primary, or in any other place in the transformer circuit where it is electrically coupled to the high frequency components of the spark producing current. Furthermore, within the scope of this invention, the energy abstracting means themselves may take forms other than that of the parallel resonant circuit shown, for instance the form of a series resonant circuit, or of a circuit from a group comprising all high-pass circuits so-called because they respond to high frequency currents above a predetermined minimum frequency.

What is claimed is:

1. In combination with a gas burner having a gas valve to open and close the gas supply to the burner, electrically energizable means for operating the valve, the burner having a pair of ignition spark electrodes and having electrical means to produce sparking between the electrodes; a control system utilizing the absence and presence of high frequency components of the spark producing current in controlling the fuel supply to the burner to effect fuel shutoff in the absence of the spark, and comprising frequency discriminating circuit means operatively associated with the spark-producing circuit for selectively abstracting energy from the high-frequency components of the spark-producing current and adapted to supply such energy during the functioning of the spark, a rectifying circuit connected across said frequency discriminating circuit means for receiving said abstracted high frequency energy for rectification and comprising a rectifier, a filtering capacitance in series with the rectifier for storing a quantity of rectified energy at a predetermined maximum control voltage, and a resistor in parallel with the filtering capacitance and adapted to automatically discharge stored energy to a lower control voltage upon cessation of the supply of abstracted rectified energy, a relay power circuit comprising a power source, an amplifier tube having at least an anode, a grid and a cathode, a solenoid coil adapted to effect the opening of the gas valve when energized while allowing the gas valve to close when de-energized, connections applying a common reference potential to one of said spark electrodes, a first terminal of said frequency-discriminating circuit means, a first terminal of said filtering capacitance, and a first terminal of said relay power source, with the polarity of said rectifier being such as to render the second terminal of said filtering capacitance positive with respect to said reference potential in response to the presence of the spark, said solenoid coil having its first terminal connected with said power source at said reference potential and its second terminal connected with the cathode of the amplifier tube, the anode of said amplifier tube being connected with the second terminal of the power source, and the grid of said amplifier tube being connected to the second terminal of said filtering capacitance, whereby with the spark absent

the amplifier tube current itself in passing through the solenoid coil produces a voltage drop biasing the cathode positive with respect to the reference potential thereby rendering that current self-limiting to a value insufficient to effect the opening of the gas valve whereas with the spark present the voltage drop appearing across the filtering capacitance increases the current through said tube and solenoid sufficiently to effect the opening of the gas valve.

2. The system according to claim 1, in which the frequency-discriminating circuit means comprises an inductance and a condenser connected

5

in parallel to constitute a resonant circuit, said circuit means being interposed between a spark electrode at said reference potential and a terminal of said spark producing electrical means.
